(57) **CLAIM**

The ornamental design for a light for an OBD2 connector, as shown and described.

DESCRIPTION

FIG. 1 is a top, front right side perspective view of a light for an OBD2 connector showing my new design;
FIG. 2 is a top plan view thereof;
FIG. 3 is a right side elevation view thereof;
FIG. 4 is a left side elevation view thereof;
FIG. 5 is a bottom plan view thereof;
FIG. 6 is a front elevation view thereof; and,
FIG. 7 is a rear elevation view thereof.

In the drawing, the paralleled grooves shown in FIGS. 1, 2, and 7 are slightly indented, and the upper circle element shown in FIG. 6 is slightly recessed.

The broken lines in the drawing are included for the purpose of illustrating environment and forms no part of the claimed design.
